MARBLE ACTUATED ROTARY WHEEL TOY

Willard A. Garbe, Oshkosh, Wis.

Application April 5, 1948, Serial No. 19,029

4 Claims. (CL. 46—42)

1

This invention relates to toys.

An object of this invention is to provide a toy in the form of a rotary wheel with a plurality of marbles or balls and means whereby the marbles or balls are released one at a time from a point at the top of the wheel so that the released balls will drop into a pocket carried by the wheel and the wheel will be rotated under the weight of the ball with the latter dropping from the pocket when the pocket is overturned. Each ball will effect at least one complete revolution of the wheel, and the wheel will continue its rotation so long as a ball is dropped into the pocket.

Another object of this invention is to provide a toy of this kind which will not only be a source of amusement, but will also be instructive and educational by teaching the power derived from the force of gravity and other factors.

A further object of this invention is to provide an improved means for successively releasing a marble or ball from the magazine or reservoir for discharge into the pocket of the wheel, and at the same time cut off or stop the remaining balls from dropping into the discharge trough until the latter is disposed in receiving position, whereupon a forward ball is released for movement into the discharge trough.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawings:

Figure 1 is a plan view of a toy or amusement device constructed according to an embodiment of this invention.

Figure 2 is a detailed side elevation of the device.

Figure 3 is a fragmentary sectional view taken on the line 3—3 of Figure 1.

Figure 4 is a fragmentary sectional view taken on the line 4—4 of Figure 2.

Figure 5 is a fragmentary sectional view taken on the line 5—5 of Figure 3.

Referring to the drawings, the numeral 10 designates generally a base constructed in the form of a tray having upstanding sides 11 and upstanding end walls 12 and 13. The tray or base 10 has fixed thereto an upwardly extending standard or support, generally designated as 14, and which comprises a pair of elongated flat bars

2

15 disposed in spaced apart relation and formed with downwardly divergent lower portions 16 terminating in vertical portions 17. The vertical portions 17 are at the lower end of the standard or support 14 and terminate in inwardly projecting lugs or feet 18 secured by fastening means 19 to the bottom wall 20 of the tray or base 10.

The parallel bars 15 are formed adjacent their upper ends with right-angularly and outwardly 10 extending members 21 and upwardly extending parallel extensions 22 extend from the outer ends of the right-angle portions 21.

A magazine or reservoir, generally designated as 23, is disposed above the base 10 and includes 15 a bottom wall 24, opposite side walls 25, and a rear end wall 26. An upwardly and rearwardly inclined bracing and supporting bar 27 is secured between the base 10 and the rear of the magazine or reservoir 23. As shown in Figure 2, the lower 20 end of the brace or support 27 includes a foot portion 28 which projects a short distance below the tray 10 so that the tray will be disposed in downwardly and forwardly inclined position in order that the balls or marbles will roll toward the front of the tray or collector 10.

The magazine 23 also includes a pair of forwardly convergent walls 29 which terminate in parallel walls 30 forming a chute or guide so that the balls or marbles will be disposed in substantial alignment for dropping of the balls or marbles one at a time onto a rotating wheel as will be hereinafter described.

The magazine 23 has fixed to the bottom wall 24 thereof a plate 31 which extends forwardly and downwardly and is provided at its forward end with upstanding ears 32 fixed by fastening means 33 to the vertical extensions 22 of the standard or support 14. The trough formed by the parallel walls 30 has fixed to the forward end 35 thereof a rockable delivery trough 34. The delivery trough 34 is pivoted as at 35 to the forward ends of the parallel walls 30 and a balancing device 36 is secured to the discharge or delivery trough 34 and projects rearwardly thereof. The balancing device 36 includes an L-shaped bar 37 having threaded thereon a weight 38 which projects rearwardly of the pivot 35. In this manner the delivery or discharge trough 34 may be maintained in substantial balance when it is empty and will be overbalanced when a ball or marble is disposed therein. The trough 30 has secured thereto an inverted U-shaped cover 39 and a stop pin 40 is fixed to an elongated plate 41 pivotally or loosely mounted as at 42 on the upper side of the cover 39. The stop member 40

projects loosely through an opening 43 formed in the top of the cover 39 and is adapted to engage a ball 44 disposed between the sides of the trough 39 before the ball is released as will be hereinafter described, for dropping into the delivery trough 34. The cover 39 also includes a right-angularly disposed and downwardly projecting stop member 45 disposed forwardly of the stop pin 40 so that when a ball is disposed in the delivery trough 34 and the latter is in its inoperative position as shown in Figure 3, the foremost ball 44 will be held against forward rolling within the trough 34. The plate or bar 41 also includes a fork 46 disposed forwardly of the stop member 45 and engaging the vertical sides of the trough 34 as shown in Figure 5. The stop member 45 includes an upwardly projecting bar 47 loosely engaging through a slot or opening 48 formed in the bar 41 between the fork 46 and the stop member 40 as shown in Figure 3. The standard or support 14 has mounted between the parallel bars 15 thereof a wheel 49 rotatably mounted on a pivot 50 extending between the parallel bars 15. The peripheral surface of the wheel or rotor 49 is of substantially spiral configuration and is formed with a sharp or abrupt cut-out 51 within which the trough 34 is adapted to drop for releasing the foremost ball or marble 44. The wheel 49 has secured thereto a pair of outwardly flared guide plates 52 which are secured to the opposite sides of the wheel 29 adjacent the cut-out 51 and the wheel 49 is also formed with a pocket 53. The pocket 53 is disposed at the forward end of the guides 52 so that a ball released from and rolling out of the trough 34 will roll onto the guides 52 and will roll lengthwise and forwardly along the guides 52 into the pocket 53. The pocket 53 is provided with a pair of flared wings 54 confronting the guides 52 so that the ball or marble rolling along the guides 52 will positively drop into the pocket 53.

In the use and operation of this device the magazine 23 is adapted to initially receive the balls or marbles and as the magazine 23 is inclined downwardly and forwardly the marbles or balls will roll into the trough 30 and the foremost ball or marble will initially strike the stop member 45 and will drop into the rear portion of the delivery trough 34. The wheel 49 is manually rotated for at least a portion of one complete revolution so that the trough 34 will drop downwardly at the front or receiving end of the pocket 53. At this time the foremost ball which was in engagement with stop member 45 will be released and at the same time bar 41 will drop downwardly so that stop member 40 will engage the next ball or marble 44 and hold the latter against forward rolling until the delivery trough 34 is raised to its inoperative position. The released ball or marble dropping into the pocket 53 will cause wheel 49 to rotate through substantially a complete turn and when trough 34 is raised upwardly to its inoperative position which is the position shown in Figure 3, stop member 40 will be raised to an inoperative position permitting the foremost ball or marble to drop into the rear of trough 34 and engage stop member 45. It will, therefore, be understood that the delivery trough is charged with a ball or marble after one ball or marble has been released so that when the wheel is rotated to position the pocket adjacent the delivery trough 34 the foremost ball will be released and the next succeeding ball held against forward movement until the delivery trough is again raised. Each ball dropping into the pocket

53 will be discharged from this pocket when the wheel 49 is rotating with the pocket on the rear side of the wheel and the released ball will drop from pocket 53 into the tray or collector 10.

I claim:

1. A toy comprising a base tray, an upstanding support fixed to said tray, a magazine fixed to the upper end of said support and disposed in a downward and forward inclination, a guide trough extending from the forward end of said magazine, a wheel rotatably carried by said support between said tray and said magazine and formed with a peripheral cutout, a pocket carried by said wheel at one end of said cutout, a delivery trough rockably disposed at the forward end of said guide trough and engaging the periphery of said wheel whereby the latter will rock said delivery trough from a downwardly inclined delivery position within said cutout to a raised receiving position spaced from said cutout, spherical wheel operating members engageable in said magazine and said guide trough, a stop member fixed relative to said guide trough and disposed forwardly of the latter in a position overlying said delivery trough whereby the foremost operating member will be held in said delivery trough when the latter is in a raised inoperative and receiving position, and means actuated by said delivery trough and adapted to engage the second operating member disposed immediately behind the foremost member upon dropping of said delivery trough to delivery position whereby the second operating member will be held against movement into said delivery trough when in delivering position and said foremost operating member will be released by said stop member for gravitating movement into said pocket for rotating said wheel.
2. A toy comprising a base tray, an upstanding support fixed to said tray, a magazine fixed to the upper end of said support and disposed in a downward and forward inclination, a guide trough extending from the forward end of said magazine, a wheel rotatably carried by said support between said tray and said magazine and formed with a peripheral cutout, a pocket carried by said wheel at one end of said cutout, a delivery trough rockably disposed at the forward end of said guide trough and engaging the periphery of said wheel whereby the latter will rock said delivery trough from a dropped delivery position within said cutout to a raised receiving position spaced from said cutout, spherical wheel operating members engageable in said magazine and said guide trough, a stop member fixed relative to said guide trough and disposed forwardly of the latter in a position overlying said delivery trough whereby the foremost operating member will be held in said delivery trough when the latter is in a raised inoperative and receiving position, and means engageable with the second operating member disposed immediately behind the foremost member upon dropping of said delivery trough to delivery position whereby the latter operating member will be held against movement into said delivery trough when in delivering position and said foremost operating member will be released by said stop member for gravitating movement into said pocket for rotating said wheel.
3. A toy comprising a base tray, an upstanding support fixed to said tray, a magazine fixed to the upper end of said support and disposed in a

downward and forward inclination, a guide trough extending from the forward end of said magazine, a wheel rotatably carried by said support between said tray and said magazine and formed with a peripheral cutout, a pocket carried by said wheel at one end of said cutout, a delivery trough rockably disposed at the forward end of said guide trough and engaging the periphery of said wheel whereby the latter will rock said delivery trough from a depressed delivery position within said cutout to a raised receiving position spaced from said cutout, spherical wheel operating members engageable in said magazine and said guide trough, a stop member fixed relative to said guide trough and disposed forwardly of the latter in a position overlying said delivery trough whereby the foremost operating member will be held in said delivery trough when the latter is in a raised inoperative and receiving position, means actuated by said delivery trough and engageable with the second operating member disposed immediately behind the foremost member upon dropping of said delivery trough to delivery position whereby the second operating member will be held against movement into said delivery trough when the latter is in delivering position and said foremost operating member will be released for gravitating movement into said pocket for rotating said wheel, and guide means fixed to said wheel and extending from said pocket for guiding an operating member into said pocket.

4. A toy comprising a base tray, an upstanding support fixed to said tray, a magazine fixed to the upper end of said support and disposed in a downward and forward inclination, a guide trough extending from the forward end of said magazine, a wheel rotatably carried by said support between said tray and said magazine and formed with a peripheral cutout, a pocket carried by said wheel at one end of said cutout, a de-

livery trough rockably disposed at the forward end of said guide trough and engaging the periphery of said wheel whereby the latter will rock said delivery trough from a depressed delivery position within said cutout to a raised receiving position spaced from said cutout, spherical wheel operating members engageable in said magazine and said guide trough, a stop member fixed relative to said guide trough and disposed forwardly of the latter in a position overlying said delivery trough whereby the foremost operating member will be held in said delivery trough when the latter is in a raised inoperative and receiving position, and means effective upon dropping of said delivery trough to delivery position and adapted to hold the second operating member disposed immediately behind the foremost member against movement into said delivery trough when the latter is in delivery position whereby said foremost operating member will be released for gravitating movement into said pocket for rotating said wheel, said means including an elongated L-shaped member pivotally disposed above said guide trough and having one side thereof projecting downwardly for engagement with said delivery trough, and a depending stop carried by the other side of said L-shaped member and disposed rearwardly of said first stop.
